UNITED STATES PATENT OFFICE.

OTIS A. MYGATT, OF NEW YORK, N. Y.

DESIGN FOR A PRISMATIC-GLASS REFLECTOR.

No. 37,960.

Specification for Design.

Patented April 17, 1906.

Application filed July 14, 1905. Serial No. 269,731. Term of patent 14 years.

To all whom it may concern:

Be it known that I, OTIS A. MYGATT, a citizen of the United States, residing at New York, in the county of New York and State of New York, have invented a certain new, original, and ornamental Design for Prismatic-Glass Reflectors, of which the following is a specification, reference being had therein to the accompanying drawings, forming part thereof.

Figure 1 is a side elevation of a reflector embodying my design. Fig. 2 is a perspective view seen from a plane slightly below the reflector.

The reflector is of transparent glass of the form shown in the drawings, and the exterior of the body is covered with reflecting-prisms, which prisms are visible on the interior of the reflector.

I claim—

The ornamental design for a glass reflector of the form shown, having external reflecting-prisms visible on the interior of the reflector, as described.

OTIS A. MYGATT.
